UNITED STATES PATENT OFFICE.

ALBERT M. JOHNSON, OF ROCKFORD, ILLINOIS, ASSIGNOR TO BARNES DRILL CO., OF ROCKFORD, ILLINOIS, A CORPORATION OF ILLINOIS.

AUTOMATIC DRILLING OR TAPPING MACHINE.

Application filed March 8, 1923. Serial No. 623,632.

The invention relates to machine tools and has especial reference to an automatic drilling or tapping machine.

The primary object of the invention is to produce a machine tool of the character indicated which operates automatically and at high speed to perform thread cutting, drilling or similar operations in or upon relatively small parts which are presented to the cutting tool or tools in rapid succession, the aim being to increase the productive capacity of machines of this character, effecting a substantial saving in time and labor, and consequently enabling the performance of such operations at a substantially lower cost than has heretofore been possible.

A special object of the invention is to provide in a machine of this character an improved mechanism for controlling the tool spindle whereby to effect its reciprocation into and out of engagement with the work with a minimum consumption of time and power.

A further object is to provide an improved means for effecting the movement of the tool spindle, which is operable to cause the descent of the spindle initially at high speed and finally as the tool is fed into engagement with the work, at a slower or working speed.

Still another object of the invention is to provide a spindle control mechanism embodying spring means for effecting a practically instant return of the spindle to its initial or uppermost position.

A further object is to provide a construction enabling the external screw threading of the work to a predetermined extent under the control of the threading tool.

The objects of the invention thus generally stated, together with ancillary advantages, are attained by the construction and arrangement illustrated in the accompanying drawings. While I have illustrated one embodiment only of the invention, it is contemplated that various changes may be made by those skilled in the art without departing from the spirit and scope of the invention as expressed in the appended claims.

In the specific embodiment of the invention herein shown, the tool spindle rotates constantly in one direction, and the means for feeding the spindle to the work is adapted for connection and disconnection with the driving means, the disconnection being

effected automatically after the completion of the screw-threading or other operation releasing the spindle to the action of spring means for restoring it to its initial position. In a copending application, Serial No. 623, 60 631 filing date Mar. 8, 1923 I have illustrated, described and claimed a form of the invention in which the direction of rotation of the spindle is reversed and in which the means for effecting the longitudinal movements of the spindle is at all times operatively associated with and actuated by the driving means.

Figure 1 of the drawings is a fragmentary side elevational view of a machine embodying my invention and equipped for cutting external screw threads. Fig. 2 is a fragmentary plan view of the rear end of the machine with a portion of the enclosing housing removed. Fig. 3 is a fragmentary 75 sectional view taken approximately in the plane of line 3 of Fig. 2. Fig. 4 is a fragmentary vertical sectional view taken in the plane of line 4-4 of Fig. 2. Fig. 5 is a similar view taken approximately in the plane of line 5-5 of Fig. 2. Fig. 6 is an underside view of the turntable for presenting the work to the cutting tool, illustrating the means for operating the table. Fig. 7 is a fragmentary side elevational view of a portion of the 80 spindle control mechanism, the turntable being shown in section. Fig. 8 is a fragmentary front view illustrating a portion of the spindle control mechanism shown in Fig. 7 and also illustrating the gearing connection 85 between the cross shaft and the main spindle. Fig. 9 is a fragmentary horizontal sectional view taken approximately in the plane of line 9-9 of Fig. 7.

The machine tool selected for purposes of 90 illustration comprises a column 10 extended forwardly at its upper end as at 11 to form a bearing or head 12 in which is mounted a sleeve 13 for up and down sliding but non-rotary movement. Within the sleeve is journaled a tool spindle 14. A collar 15 fast upon the spindle bears upon the upper end of the sleeve, and interposed between the lower end of the sleeve and the spindle is a ball thrust bearing 16.

Extending rearwardly from the column 10 and supported partially thereby and by a standard 17 is a housing or case 18 (Fig. 2) in which is mounted a drive shaft 19 operatively connected by miter gears 20 and 21 105 110

with a change speed transmission including a pair of parallel shafts 22 and 23 provided with suitable intermeshing and shiftable gearing whereby power is transmitted from the drive shaft 19 to the shaft 23. The upper end of the latter has fast thereon a bevel pinion 24 meshing with a bevel gear 25 splined on the spindle 14 near the upper end thereof. The shafts 22 and 23 are inclined upwardly and forwardly as shown clearly in Fig. 1 and are enclosed by a suitable casing 26 which extends forwardly to enclose also the gears 24-25.

The articles constituting the work are presented with a step-by-step movement to the operation of the cutting tool—herein a self-opening die designated by the numeral 27—and this work-presenting means includes a turret or turntable 28 suitably mounted upon a stationary frame 29 which in turn is carried by a table 30 superposed upon a chip pan 31, the whole being carried by a support 32 mounted for vertical adjustment upon the column 10. The frame 29 upon the table 30 encloses means for advancing the work to present it to the cutting tool, which means is actuated in the reciprocation of a bar 33 connected by a link 34 and a crank arm 34^a with the main control mechanism of the machine to be presently described.

Referring to Figs. 1 to 5, the drive shaft 19, mounted in bearings 35 and 36 rising from the bottom of the case 18, is connected by means of a pinion 37 fast thereon, and a spur gear 38, with a toothed element or head 39. The gear 38 is fast upon a sleeve 40 mounted in a bearing 41 on an axis parallel to the shaft 19; and the stud shaft 42 is journaled in the sleeve 40 and in the present instance is made rigid with a drum 43 apertured at one end to receive a shaft 44 rigidly secured to the drum as by means of a screw 45. Said shaft 44 carries the crank arm 34^a at its free end and is mounted in a bearing 46 which, with the bearing 41, is suitably supported in the case 18 rising from the bottom thereof. It will be observed that relative rotation is permitted between the sleeve 40 and the drum 43.

Means is provided, however, for establishing an operative connection between the sleeve and the drum through the head 39, and this means in the present instance, comprises a series of ratchet teeth 47 and a member 48 carried by the drum adapted to engage with the teeth 47. This member 48 is pivoted at 49 in a diametrical slot 50 provided in the drum and constitutes a dog normally actuated by a compression spring 51 for effecting a positive driving connection between the sleeve and drum. Said spring 51 is entered in a suitable socket 52 in the drum and its free end engages the dog 48.

The free end of the dog projects a substantial distance beyond the periphery of the

drum 43, and mounted upon opposite sides of the drum are a pair of stop pins 53 and 54 one of which is at all times positioned in the path of movement of the free end of the dog 48 when the latter is rotated with the drum 43. Said pins 53 and 54 are carried in arms 55 and 56 respectively, fast upon a rod 57 which is slidable in a bearing bracket 58 formed integral with and rising from the bearing 41. For this purpose the bracket 58 is provided with suitable bearing sleeves 59 and 60, and also has a pair of forwardly extending arms 61 each having a bearing sleeve 62 in which the stop pins 53, 54 are respectively slidable. As shown in Fig. 2, the dog 48 has its free end beveled upon its side adjacent the teeth 47 in order readily to engage therewith and also to form a cam surface which is adapted to coact with the stop pins 53, 54. Preferably also, these stop pins are provided with beveled faces complementary to the beveled faces of the dog 48 and serve as cam members adapted in the movement of the dog as aforesaid to effect the disengagement of the dog from the teeth 47 whereby to effect the stoppage of the drum 43.

The pins 53, 54 are arranged to be moved alternately under the control of the spindle 14 into the path of movement of the dog 48 by means to be presently described, for the purpose of effecting the intermittent rotation of the drum and a pair of cams 63 and 64 fast upon the shaft 44.

The cams 63 and 64 are adapted to effect the downward movement of the spindle first at a relatively high speed and then at a low or working speed. To this end the cam 63 operatively engages with a roller 65 upon the free end of a lever 66 fast upon a rock shaft 67 which is suitably mounted in a bracket 68 carried by the housing 26 at the lower rear end thereof. Upon said rock shaft 67 is made rigid a gear segment 69 meshing with a spur pinion 70 which latter is journaled upon a stud shaft 71 in a bearing 72 also carried by the bracket 68. Rigid with the pinion 70 is a sprocket gear 73 connected by a chain 74 (Figs. 1 and 7) with a sprocket wheel 75 mounted to travel upon the threaded end 76 of a cross feed shaft 77. An adjustable stop 78 having a boss 79 is adapted for engagement by a lug 80 on the sprocket 75. The arrangement is such that as the sprocket is rotated through the operation of the cam 63, it also moves outwardly until the lug 80 engages the boss 79. The effect, it will be seen, is to lock the sprocket to the shaft and impart rotary movement thereto. Thus an adjustable lost-motion connection is provided between the cam 63 and the spindle, or more specifically between the sprocket 75 and the shaft 77. When the spindle moves upwardly as hereinafter set forth, the shaft 77 is rotated in a reverse di-

rection and causes the sprocket wheel 75 to move away from the stop 78.

Fast upon the shaft 77 is a spur pinion 81 (Fig. 7) which meshes with a rack 82 formed integral with the sleeve 13 upon the rear side thereof. The arrangement is such that in this operation of the cam 63, the spindle is initially moved downwardly at a relatively high speed, and then due to a dwell 63' in the cam the downward descent of the spindle ceases momentarily while the other cam 64 comes into operation to effect a continuation of the downward descent of the spindle but at a slow or working speed. This latter cam 64 is arranged to operate upon a roller 83 mounted in a shoe 84 (Fig. 4) which is mounted upon the cam shaft 44 for relative transverse sliding movement as permitted by slots 85 formed in opposite sides of the shoe. Rigid with the shoe and extending upwardly and forwardly therefrom is a rod 86 entered through the lower end of the housing 26 and emerging from the housing near its upper end, at one side thereof, the housing being reduced in size for this purpose. Said rod is connected at its upper end to a lever 87 (Fig. 1) pivoted upon a stud 88 projecting outwardly from the side of the housing 26, and the lever 87 in turn is operatively connected to a bracket 89 pivoted upon a shaft 90. Within the housing 26 is mounted a worm gear 91 meshing with a worm 92 fast upon the driven shaft 23 of the change speed mechanism. Also mounted on the shaft 90 rigid therewith is a spur gear 93 which is connected by a gear train 94, 95 and 96 with a horizontal shaft 97 connected by bevel gearing 98 with a vertical shaft 99. The latter has at its lower end a worm 100 adapted to mesh with a worm wheel 101 on a shaft 102 (Figs. 1 and 8). The gears 94, 95, 96, and the worm 100 with its connection with the gear 96, are all mounted upon the bracket 89, and since the spur gear 93 is coaxial with respect to this bracket, it will be seen that the bracket may be swung through its connection with the lever 87 to carry the worm 100 into and out of mesh with the worm wheel 101, the cam 64 being adapted to move the rod 86 and with it the free end of the lever 87 downwardly to effect the desired interengagement of the worm 100 with the worm wheel 101. Normally the worm 100 is held out of mesh with the worm wheel 101 by a coiled expansion spring 103 encircling the upper forward end of the rod 86 and bearing between the casing 26 and the pivot stud by which the rod is connected to the lever 87.

The connection between the lever 87 and the bracket 89 comprises a coiled compression spring 103 which, in the present instance, is entered within a tubular portion 104 of the lever 87 and operates through a

plunger 105 against an abutment 106 on the bracket. It will be apparent that this spring 103 in the lever 87 constitutes a yielding connection between the lever 87 and the bracket 89 such that in the event of a failure of the worm 100 to mesh properly with the worm wheel 101, the parts are saved from injury.

The shaft 102 upon which the worm gear 101 is mounted is operatively connected with the cross feed shaft 77 through a reduction gearing (Fig. 8) to effect the desired slow working feed of the spindle. This reduction gearing comprises in the present instance a pinion 107 fast upon the shaft 102 and meshing with an internal gear 108 formed within a housing member 109 fast upon the shaft 77.

It will be seen that to effect the first or initial downward movement of the spindle, the cam 63 operates to rotate the sprocket 75 threaded upon the shaft 77. Such initial movement of the spindle does not commence, however, until the sprocket in its travel on the screw-threaded portion of the shaft interengages with the adjustable stop 78. Thus the position of the stop on the shaft determines the extent of the movement of the spindle by the cam 63. A momentary cessation in the downward movement of the spindle occurs after such initial movement, due to a dwell in the cam 63, and at this time the cam 64 comes into operation to swing the worm 100 into mesh with the worm wheel 101. Thus in the final or downward movement of the spindle the shaft 77 is rotated from the chain speed mechanism through gearing 91—94, etc., and the reduction gearing 107—108.

Upon the completion of the operation of the cam 64, the spindle is released for upward movement, returning to its initial position through the operation of a coiled compression spring 110 encircling the upper end of the spindle and bearing between a clamp nut 111 and the gear 25 operating in the upper end of the forwardly extended portion of the housing 26. It will be apparent that the return of the spindle is thus effected almost instantly upon its being released by the operation of the cam 64.

Such release by the cam 64, however, is under the control of the spindle in its downward movement, the arrangement being such that when the spindle approaches a predetermined point in its downward travel, that is to say, when a thread of a predetermined length has been cut by the tool 27, the cam 64 is set in motion to effect the release of the spindle. On the other hand, the return of the spindle to its initial position is arranged to permit the initial operation of the cam 63 to effect the downward movement of the spindle. This control means will now be described.

As hereinbefore set forth, the cross feed

shaft 77 is extended outwardly beyond the housing 109 and screw-threaded as at 76 (Fig. 8). Upon this screw-threaded portion of the spindle I provide in addition to the stop 78 a pair of stops 112 and 113 between which travels a nut 114, the stops and nut being provided with interengageable bosses 112^a, 113^a and 114^a. The nut is operatively connected, through an arm 115 and a link 116 (Fig. 7), with the rod 57 which operates the stop pins 53 and 54 of the main control mechanism. The lowermost position to which the spindle may travel may be predetermined by adjusting the stop 112 in accordance with the length of the thread to be cut or the depth of the hole to be drilled. When such position is reached, the nut 114 will engage with the stop 112, and the resulting rotation of the nut will move the rod 116 upwardly and forwardly to disengage the dog 48 from the stop pin 53, releasing the dog for engagement with the teeth 47 of the head 39. In the ensuing rotation of the head, the cam shaft 44 is rotated, and in such movement of the cam shaft the cam 64 moves free of the roller 83 allowing the spring 103^a to effect the disengagement of the worm 100 from the worm wheel 101.

The spindle now travels upwardly, and through the operation of the cross feed shaft 77 turns the sprocket 75 to restore the lever 66 to its initial position (Fig. 4). As the spindle approaches its uppermost position, the nut 114 engages with the stop 113, moving the rod 57 downwardly and rearwardly to move the stop pin 54 out of the path of movement of the dog 48. It will be observed that upon the disengagement of the cam 64 from the roller 83, the shaft 44 rotates approximately through 180 degrees to position the cam 63 for almost instant engagement with the lever 66. Hence upon the return of the spindle to its uppermost position the cam 63 operates immediately to start the spindle downwardly under high speed, and the operation of the cam 64 follows to continue the descent of the spindle at working feed.

I have shown a means whereby the operation of the nut 114 in the downward movement of the spindle, instead of occurring as a result of its travel into engagement with the stop 112, is effected by the operation of the self-opening die 27. Thus a lever 117 is pivoted at 118 upon a suitable bracket 119 so as to swing in a horizontal plane with one end lying adjacent the periphery of the lower end of the self-opening die 27. In this die is mounted a plurality of thread cutting devices or "chasers" which are arranged to move outwardly so as to project from the periphery of the die upon the opening thereof. Said lever 117 is connected by means of a bell crank 121 also pivoted upon the brack-

et 119 with a rod 122, the latter being pivoted at its upper end to an arm 123 rigid with the nut 114. The latter, it will be remembered, is connected with the operating rod 57 of the control mechanism so that operation of the cam 64 to interrupt the working feed and release the spindle occurs instantly upon the completion of the desired thread-cutting or other operation.

The self-opening die 27 may be of any suitable character. That herein shown is of a well-known type comprising generally an outer cam sleeve 124 operatively associated on the one hand with the chasers 120 and on the other hand with a trip member 125 adapted to engage with the work, when a predetermined length of thread has been cut to impart movement to the cam sleeve 124 whereby to effect the movement of the chasers into position to engage the lever 117. 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 tion of the cams 63 and 64 much more rapidly than is possible with the gear feeds of the prior art; and the return of the spindle to its initial position by the spring means which I have provided, is practically instantaneous. Obviously, therefore, the productive capacity of the machine is very high; also, notwithstanding the rapid operation of the machine, the thread cutting or other work to be done is performed with a high degree of precision.

I wish especially to point out that while the invention has been described more particularly with reference to a machine for cutting screw threads, it is capable of use for performing other operations as well.

I claim as my invention:

1. In a machine tool, the combination with a reciprocating spindle, of a rotary element having a gearing connection with the spindle and two separate cam means operable to effect rotation of said element, a follower associated with one of said cam means and having a connection with said element to rotate it at high speed, a second element constantly driven and normally disconnected from the first element, the other cam means being operable to effect a driving relation between the second element and the first element substantially upon the completion of the operation of the first cam means.

2. In a machine tool, the combination with a reciprocating spindle, of driving means operable to rotate the spindle constantly in one direction, a rotary element having an operative connection with said spindle to move it longitudinally, a second rotary element operatively associated with said drive means, and cam means having a connection with the first element to rotate it and an operative connection with the second element to move it into driving relation with the first element.

3. In a machine tool, the combination of a spindle mounted for reciprocation, a feed shaft having a gearing connection with the spindle, said feed shaft having a driving gear thereon, means operatively connected with a source of power and including a gear element movable into and out of operative association with said driving gear, and intermittently operating means to effect successively the rotation of said feed shaft at one speed and the engagement of said gear element with the driving gear to rotate the feed shaft at another speed.

4. In a machine tool, the combination of a spindle, a feed shaft having a driving engagement with the spindle to move it longitudinally, means including a cam operating to rotate said feed shaft whereby to move the spindle initially at high speed, and cam controlled means for continuing the movement of the spindle at slow or working feed, the first cam during the final portion of its

operation being effective to move the spindle while the second cam starts functioning.

5. A machine of the character described comprising, in combination, a spindle, feed mechanism for the spindle including a rotary element in driving relation thereto, power driven means for effecting the rotation of said element including a constantly rotating driver, a member arranged for positive connection with the driver and having an operative connection with said feed element to move it, and a device operable to effect such connection of the driven member with the driver and adapted to automatically interrupt such connection upon the completion of a predetermined range of movement of the driven member by the driver.

6. A machine of the character described comprising, in combination, a spindle, feed mechanism for the spindle including a rotary element in driving relation thereto, power driven means for effecting the rotation of said element including a constantly rotating driver, a cam member arranged for positive connection with the driver, means actuated by said cam member to rotate said feed element, and a device operable to effect such connection of the driven member with the driver and adapted to automatically interrupt such connection upon the completion of a predetermined range of movement of the driven member by the driver, said device being operatively associated with the spindle so as to be actuated thereby as the spindle approaches a predetermined point in its travel.

7. In a machine tool, the combination of a reciprocating spindle, a drive shaft, a driven shaft, said drive shaft being connected with the spindle to rotate it, and means for moving the spindle longitudinally including a reduction gearing having a direct connection at all times with the drive shaft and a disengageable connection with the spindle, and cam means actuated from the driven shaft and adapted to effect a connection between the reduction gearing and the spindle.

8. A machine of the character described, having a spindle and a normally disengaged feed mechanism therefor, power driven means for engaging the feed mechanism including a constantly rotating driver, a member arranged for positive connection with the driver and operatively associated with the feed mechanism, and a device operable to effect such connection of the driven member with the driver and adapted to automatically interrupt such connection when the feed mechanism has become engaged.

9. A machine tool having a longitudinally movable spindle, means for moving the spindle longitudinally including a gear mounted on a fixed axis, a pivoted bracket having a gear thereon movable into and out of mesh

with the first mentioned gear, spring means tending to move said bracket in one direction to hold said gears out of mesh, and cam means for moving the bracket in the opposite direction to effect the intermeshing of the gears, said cam means being operable to release the bracket to the action of the spring means at a predetermined point in the movement of the spindle.

10. 10. In a machine tool, the combination of a spindle, and means for moving the spindle longitudinally including a gear operatively connected with a source of power, a bracket upon which said gear is mounted, and means also connected with the source of power for swinging said bracket including a lever and a spring interposed between said lever and said bracket.

11. In a machine tool, the combination of 20 a spindle, and means for moving the spindle longitudinally including a gear operatively connected with a source of power, a bracket upon which said gear is mounted, means for swinging said bracket including a lever and 25 a spring interposed between said lever and said bracket, and means also connected with the source of power for swinging the lever whereby to actuate said spring to cause it to swing the bracket.

12. A machine tool having a reciprocating spindle, a constantly driven shaft, a pivoted bracket having a gear element operatively connected with said shaft, a feed shaft having a gearing connection with the spindle 35 and having a gear element with which the first gear element is adapted to mesh, and cam means initially acting directly to rotate the feed shaft and then swinging said bracket to effect the interengagement of said gear elements.

13. In a machine tool, the combination of a spindle, a shaft having a gearing connection with the spindle to move it longitudinally, and means for rotating said shaft 45 including a gear element, a member rigid with said gear element, a cam engaging said member for actuating said gear element, and means including feed gearing providing an operative connection between said gear element and said shaft.

14. In a machine tool, the combination of a spindle, a shaft having a gearing connection with the spindle to move it longitudinally, and means for rotating said shaft 55 including two intermeshing gear elements, a cam for actuating one of said gear elements, and a chain and sprocket connection between the other one of said gear elements and said shaft.

15. In a machine tool, the combination of a spindle, and means for moving the spindle longitudinally including a shaft having a gearing connection therewith and also a threaded portion, a gear element mounted 35 on the threaded portion of the shaft, a stop

adjustable on the shaft, and means for rotating said gear element into engagement with said stop for rotating the shaft.

16. In a machine tool, the combination of a spindle, and means for moving the spindle longitudinally including a screw-threaded member, a second member screw-threaded on the first member and operatively connected with a source of power for rotary movement, and means for varying the extent of the independent rotary movement of the second member upon the first member whereby to vary the extent of movement of the spindle.

17. In a machine tool, the combination of a spindle, means for moving the spindle longitudinally including a cam, and means providing an adjustable lost motion connection between the cam and the spindle whereby to vary the extent of movement of the latter.

18. In a machine tool, the combination of a spindle, feed mechanism for the spindle including a feed shaft operatively connected with the spindle, and means for actuating said feed mechanism comprising a driven shaft, a cam on said shaft, means providing an operative connection between said cam and said feed shaft, a drive shaft, and means under the control of the spindle for effecting a positive driving connection between the driven shaft and the drive shaft.

19. In a machine tool, the combination of a spindle, feed mechanism for the spindle, including a screw-threaded shaft, a nut mounted to travel on said shaft in the movements thereof, stop means on the shaft adapted to limit the travel of the nut, a drive shaft, means for moving the spindle longitudinally including a cam operatively associated with said feed mechanism, and means arranged to be actuated by said nut and adapted to effect a rotation of said cam by the drive shaft.

20. In a machine tool, the combination of a spindle, means for moving the spindle longitudinally including a shaft having a gearing connection with the spindle, means for directly rotating the shaft to effect its rapid movement, a gear element operatively connected with a source of power, reduction gearing associated with said shaft, and means for moving said gear element into and out of operative relation relative to said reduction gearing.

21. A machine tool having, in combination, a tool spindle mounted for reciprocating movements, a feed shaft connected with the spindle to move it longitudinally, a gear element having a driving connection with the shaft, a second gear element operatively associated with the first gear element, a constantly rotating drive element, a cam having a disengageable connection with the drive element and adapted to actuate said second

gear element whereby to impart movement to the spindle, and means operable at a pre-determined point in the movement of the spindle for governing the connection between said cam and said drive element.

22. In a machine tool, the combination of a spindle, means for moving said spindle longitudinally including a cam having a follower with a driving connection with the spindle, a constantly rotating element having a disengageable connection with said cam, and means controlled by the movements of said spindle for intermittently connecting and disconnecting said cam and said constantly rotating element.

23. In a machine tool, the combination with a part to be moved in one direction, of a cam, a follower for the cam having a driving connection with said part to move it in the operation of the cam, a constantly rotating element, and means controlled by the movement of said part to effect the positive connection and disconnection of said cam to and from said element at predetermined points in the operating cycle of said cam.

24. In a machine tool, the combination of a pair of cams, a follower for one of said cams having a driving connection connected with a part to be moved, and means connected with a source of power and constituting an additional means for moving said part, the other cam being adapted to control the operation of said additional means.

25. In a machine tool, the combination of a constantly rotating element, a shaft having a pair of cams thereon, a follower for one of said cams having a driving connection connected with a part to be moved, means connected with a source of power and constituting an additional means for moving said part, the other cam being adapted to control the operation of said additional means, and means controlled by the movements of said part for effecting the intermittent rotation of said cam shaft.

26. A machine tool having, in combination, a reciprocating spindle and two separate means for effecting the longitudinal movement of the spindle, one of said means including a cam having a follower with a driving connection with the spindle, and the other means including a feed mechanism and a second cam controlling the same, said cams being successively operable so that upon the completion of the movement of the spindle by the operation of one cam, the continued movement of the spindle is effected by the operation of the other cam.

27. In a machine tool, the combination of a spindle, spring means tending to move the spindle in one direction, and means for moving the spindle in the opposite direction including a member having a pair of cams

rigid therewith, a constantly rotating element, and means controlled by the movements of the spindle in opposite directions for effecting a positive driving connection between said member and said element.

28. In a machine tool, the combination of a spindle, means tending to move the spindle in one direction, and means for moving the spindle in the opposite direction including a member having a pair of cams rigid therewith and driving means for the member having a disengageable but positive connection therewith, and means controlled by the movements of the spindle for interrupting the operation of said member by said driving means.

29. In a machine tool, the combination of a spindle, spring means tending to move the spindle in one direction, cam means for moving the spindle in the opposite direction, driving means having a positive but disengageable connection with said cam means, and means controlled by the movements of the spindle for governing the operation of said cam means by said driving means.

30. In a machine tool, the combination of a longitudinally movable spindle, a constantly driven element, a shaft having cam means operatively associated with the spindle to move it, means providing a connection between the cam shaft and said constantly rotating element including a driving dog, a stop pin movable into and out of the path of movement of said dog and adapted to move it out of operative association with said element, and means controlled by the spindle for controlling the position of said stop pin.

31. In a machine tool, the combination of a longitudinally movable spindle, a constantly driven element, a member having cam means thereon, a driving dog operatively associated with said element and said member whereby the latter may be driven by the former, a stop pin adapted for engagement by said dog to effect the movement of the latter into inoperative position, means operatively connected with the spindle for moving said stop pin to release the dog, and means operatively associated with said cam means for imparting movement to the spindle.

32. The combination of a spindle mounted for longitudinal movement, means including a cam operatively connected with the spindle to move it, a constantly driven element, means including a driving dog for effecting a connection between said element and said cam, and means controlled by the movements of the spindle for effecting the movement of said dog into and out of operative association with said element.

33. The combination with a spindle, a driving means, a cam, a follower for said cam having a driving relation with the spin-

dle to move it, means operatively connected with the driving means to move the spindle, a second cam for controlling the last mentioned means, and means controlled by the movements of the spindle for rotating the cams, the arrangement being such that the first mentioned cam operates to effect the initial rapid movement of the spindle and the means controlled by the second cam operates in continuation of such rapid movement to move the spindle at a slow or working feed.

34. In a machine tool the combination of a spindle, a driving means, a driven element connected with the driving means, means including a cam operatively connected with the spindle to move it, means operatively connected with the driving means and constituting an additional means for moving the spindle, a second cam for controlling the last mentioned means, means for rotating said cam including a driving dog arranged for operative engagement with said driven element, a stop pin arranged for engagement by said dog and adapted to govern the position of the latter, and means for controlling the position of the stop pin in accordance with the position of the spindle.

35. In a machine tool, the combination with a spindle and a tool carried thereby having a cutter adapted to move radially when disengaged from the work; of means for imparting movement to the spindle including a constantly rotating element, a second element operatively connected with the spindle, and means controlled by the radial movement of said cutter for controlling the connection between said elements, said means including a driving dog between said elements, a stop pin adapted to be engaged by said dog, and a part disposed in the path of movement of said cutter in the inoperative position thereof to control the position of said stop pin.

36. In a machine tool having a spindle, a cutting tool carried by the spindle, having radially movable cutters, of means for feeding the spindle and cutting tool to the work, and means operable by the disengagement of the cutter from the work to interrupt the feeding of the spindle.

37. In an automatic thread cutting machine, the combination of a tool spindle, and a tool carried thereby having a cutter movable radially upon the completion of a predetermined thread cutting operation, of means for feeding the spindle and tool to the work, and means controlled by the disengagement of said cutter to interrupt the operation of the spindle feeding means.

38. In a machine tool, the combination of a spindle, means for moving the spindle in one direction comprising a rotary part having a gearing connection with the spindle

and a cam having a follower with a driving connection with said part, a constantly rotating drive element having a disengageable connection with said cam, and means operative in the movement of the spindle to connect and disconnect said element and said cam.

39. In a machine tool, the combination of a spindle mounted for longitudinal movements, a spring tending to move the spindle in one direction, means for moving the spindle in the opposite direction including a cam, a constantly rotating drive element having a disengageable connection with said cam, and means operable by a movement of the spindle by said spring to effect a connection between said cam and said drive element.

40. In a machine tool, the combination of a spindle mounted for longitudinal movements, feed mechanism for the spindle to move it in one direction, and means for controlling the operation of the spindle by said feed mechanism including a cam, a constantly rotating drive element, and means actuated upon a predetermined movement of the spindle whereby to effect a connection between said cam and said element and thereby render said feed mechanism operable.

41. In a machine tool, the combination of a part mounted for reciprocation, feed mechanism for said part, means for driving said feed mechanism and having a disengageable connection therewith, spring means normally holding the driving means in inoperative relation to the feed mechanism, and means under the control of said part to effect a connection between said feed mechanism and its driving means.

42. In a machine tool, the combination of a part mounted for reciprocation, feed mechanism for said part, means for driving said feed mechanism and having a disengageable connection therewith, spring means normally holding the driving means in inoperative relation to the feed mechanism, and means under the control of said part to effect a connection between said feed mechanism and its driving means, the last-mentioned means comprising a constantly rotating drive element, a cam operatively associated with said driving means to move it against the operation of said spring means, and means operating upon a predetermined movement of said part to disconnect said cam from its drive element.

43. In a machine tool, the combination of a spindle mounted for longitudinal movements, a constantly rotating drive element, a shaft having a pair of cams thereon, means associated with one of said cams to move the spindle in one direction at an initial high speed, means associated with the other cam

adapted to continue the movement of the spindle but at a low speed, spring means for moving the spindle in the opposite direction, and means operable in the movement of the spindle by said spring means to effect a driving connection between said drive element and the cam shaft.

44. In a machine tool, the combination of a part mounted for reciprocation, feed mechanism for said part, driving means, cam means for establishing an operative connection between said driving means and said feed mechanism, spring means tending to maintain the driving means disconnected from the feed mechanism, and means for operating said cam means intermittently for

effecting a connection between the feed mechanism and its driving means.

45. A machine tool having, in combination, a tool spindle mounted for reciprocatory movements, a feed shaft having a gearing connection with the spindle to move it longitudinally, a gear element in driving relation with the feed shaft, a second gear element meshing with the first gear element, and a cam operatively connected with a source of power and having means to actuate said second gear element to rotate said feed shaft.

In testimony whereof, I have hereunto affixed my signature.

ALBERT M. JOHNSON.
